I claim a trash can mounted vacuum recovery system for loose-fill packaging material, as shown and described.

DESCRIPTION

FIG. 1 is a top and right side perspective view of a trash can mounted vacuum recovery system for loose-fill packaging materials showing my new design;

FIG. 2 is a front elevational view thereof;

FIG. 3 is a rear elevational view thereof;

FIG. 4 is a top plan view thereof;

FIG. 5 is a left side elevational view thereof; and,

FIG. 6 is a right side elevational view thereof.

The hose shown broken away in FIGS. 1 and 4-6 is understood to represent indeterminate length.

The portion depicted in broken lines in FIG. 1 (i.e., the trash can and the electric cord and switch) forms no part of the design.

The bottom of the vacuum recovery system of the present invention is plain and unornamented.
